UNITED STATES PATENT OFFICE.

JAMES I. LEARY, OF CHICAGO, ILLINOIS.

MACHINE FOR PRINTING AND MOISTENING ADHESIVE WRAPPING-TAPE.

1,116,084.

Specification of Letters Patent.

Patented Nov. 3, 1914.

Application filed April 23, 1914. Serial No. 833,847.

To all whom it may concern:

Be it known that I, JAMES I. LEARY, a citizen of the United States, residing at Chicago, in the county of Cook and State of Illinois, have invented certain new and useful Improvements in Machines for Printing and Moistening Adhesive Wrapping-Tape, of which the following is a specification.

This invention relates to machines for printing and moistening wrapping tape and its object is to provide a machine of simple and inexpensive construction, which comprises few parts, which is easy to operate and which will not readily get out of order.

In addition to the general object of the invention it also has in view to provide simple means for adjusting the tension on the spool of tape, for adjusting the tension of the printing roll and for moistening the free end of the tape before a section thereof is removed.

With these and other ends in view the invention consists of the novel construction and arrangement of parts hereinafter described and illustrated in the accompanying drawings in which—

Figure 1 is a side elevation of the machine, partly in section and partly broken away, and Fig. 2 is a detailed sectional view through the tape spool showing the adjusting means.

Referring to the drawings, a suitable frame 3 in which all the parts are mounted comprises two side members 4, 5 which are held together and spaced apart by three bolts 6.

The tape 7 consists of a paper strip coated with adhesive on one side and wound in the form of a roll 8 which is mounted in a spool supported to revolve on one side 4 of the frame which extends upwardly for this purpose. A shaft 9 provided with a shoulder 10 projects through the frame side 4 and is screw-threaded to receive the nut

11 by which the shaft is rigidly fixed to the frame. A sleeve 12 is arranged on the shaft and its inner end abuts against the shoulder 10. A spool end 13 is rigid with the inner end of the sleeve and engages the shoulder 10. Another spool end 14 is loosely mounted on the sleeve on the opposite side of the roll 8 and a nut 15 is screw-threaded on the outer end of the sleeve to engage the spool end 14. By adjusting this nut 15 the spool ends may be caused to engage the sides of the roll of tape. The

shaft 9 is interiorly threaded at the end adjacent to the nut 15 to receive a screw 9' which engages the outer end of the sleeve 12, whereby the tension of the tape may be adjusted by tightening or loosening the sleeve on the shaft. To place a roll of paper in the machine the nut and screw 15 and 9' and the spool end 10 should be removed.

The paper passes down from the roll at the front of the machine to and around an impression roll 16, thence up and over the paper roll and then down and under a guide roll 17 and forwardly over the moistening roll 18 and beneath the cutting edge 19. A printing roll 20 is yieldingly supported beneath the impression roll 16 to print upon the paper as it passes around the impression roll. This printing roll is supplied with suitable type and is inked by the gravity inking rolls 21 removably mounted in the frame and operating freely therein. The printing roll is mounted on a shaft 22 which projects through slots 23 in the sides of the frame and spring arms 24 engage the projecting ends of the shaft and yieldingly press the printing roll against the tape, so that said roll will turn with the impression roll and the tape to print upon the tape. The yielding spring arms 24 are parts of spring wires 25 which are coiled on the studs 26, in each side of the frame, and which project rearwardly to engage rack teeth 27 on the sides of the frame, whereby the tension of the spring arms may be adjusted.

The moistening roll 18 is mounted in the frame to work in a bath of water contained in a removable trough 28, so that the adhesive side of the tape will be moistened in passing over the roll 18 as the tape is drawn over the machine. A cutter 19 is arranged adjacent to the moistening roll so that when a strip of tape has been drawn outward it can be easily removed by tearing it along the cutting edge 19.

It will be observed that the end of the tape always extends forwardly of the moistening roll and if the machine was not used for some time the adhesive on this projecting end of the tape would become dry and not adherent when a section of the tape was later removed. In order to moisten this projecting end of the tape before a section of the tape is removed from the machine I provide a sponge 29 located in a

small compartment 30 at the forward end of the trough 28 and a small hole 31 in the partition 32 which separates this sponge compartment from the water compartment 33, so that water may trickle through and keep the sponge constantly moist. Just before a section of the tape is removed from the machine the projecting end should be pressed into engagement with the sponge to moisten the adhesive thereon after which the tape can be withdrawn as desired.

It will be observed that all the parts of the machine are removably mounted in the frame so that they can be readily removed as occasion may require and that the adjustment of the various parts can be regulated as desired.

I claim:

In a machine of the character described, 20 the combination of a frame, a spool for holding a roll of tape supported in the up-

per part of the frame, an impression roll mounted in the frame below the spool, a printing roll mounted in the frame below the impression roll, a shaft for said printing roll having its ends projecting through slots in the sides of the frame, studs projecting outwardly from the sides of the frame, spring wires mounted on said studs and having arms projecting forwardly beneath the shaft for the printing roll to press said roll upwardly against the tape on the impression roll, and rack teeth on the sides of the frame, said wires being coiled on said studs and projecting rearwardly to be engaged with said teeth, substantially as described.

JAMES I. LEARY.
